UNITED STATES PATENT OFFICE.

BERG HEINRICH, OF ANDERSON, INDIANA, ASSIGNOR TO MID-WEST BOX COMPANY,
OF ANDERSON, INDIANA, A CORPORATION OF INDIANA.

BOX-SEALING MACHINE.

1,355,227.

Specification of Letters Patent.

Patented Oct. 12, 1920.

Application filed September 8, 1919. Serial No. 323,534.

To all whom it may concern:

Be it known that I, BERG HEINRICH, a citizen of the United States, and a resident of Anderson, in the county of Madison and 5 State of Wisconsin, have invented certain new and useful Improvements in Box-Sealing Machines, of which the following is a full, clear, and exact description.

The invention relates to machines for 10 sealing boxes.

One object of the invention is to provide a machine or press which is adapted to seal boxes, is simple in construction and can be operated with facility.

15 The invention consists in the several novel features hereinafter set forth and more particularly defined by claims at the conclusion hereof.

In the drawings: Figure 1 is a section, 20 parts being shown in elevation. Fig. 2 is a plan. Fig. 3 is a section taken on line 3—3 of Fig. 1.

The invention is illustrated in a machine comprising a rotatable series of presses each 25 adapted to hold a box while it is being sealed. A rotatable mast 6 is rotatably held in base 7 and is adapted to support the series of presses. Each press or sealing unit comprises a lower member 8 and a coacting member 9 between which the box is adapted 30 to be held while it is being sealed.

Each lower press-member 8 is supported by a standard 10 which is held in a guide-bracket 11 which is secured to the underside 35 of a supporting arm 12. All of said arms are secured by bolts 13 to a carrier or hub 14 which is secured to the mast 6 by a set-screw 15. Each member 8 has secured, to its underside, a socket 16 adapted to receive 40 the upper end of a standard 10 and the latter is provided with a pin 17 on which the socket rests. Members 8 are usually formed of wood and cleats 8^a are secured thereto. These members are removably held on the 45 standards 10 respectively, so that members for different sizes of boxes can be readily substituted. The socket 16 and pin 17 facilitate the interchange of these members. Standard 10 is square and the opening 50 through which it passes in socket 16 is correspondingly formed. The square standard 10 also passes through a square opening 18 in guide 11 so that the standard 10 is vertically adjustable in said guide so that the 55 press-member 8 may be adjusted to adapt it

for boxes of different heights. A set-screw 19 and a shoe 20 engaged by said screw are adapted to secure the stem 10 in assigned position in the socket 11. This connection between the press-member 8 and the stem 60 10 exemplifies one which permits the member to be quickly removed or replaced.

Each upper press-member 9 is supported from a sleeve 21 through which the mast 6 passes and by which it is adjustably sustained by a pin 22 and a series of holes 23 in the mast. This pin-connection exemplifies one which permits the sleeve and all of the upper press-members supported therefrom to be conjointly vertically adjusted relatively to the lower press-members 8 to adapt the press for boxes of different heights.

There is a supporting and operating connection between the sleeve and each of the 75 press-members 9 respectively and each of these connections comprises an arm 25 made up of a pair of bars 26 rigidly secured together in spaced relation by cross-studs 27. The inner end of each arm 25 is pivotally 80 connected to the lower portion of the sleeve 21 by a pin 28 which passes through a lug 29 on the sleeve and through the bars 26 of said arm. Press-member 9 is suspended from a pin 30 which passes through the 85 front ends of the bars 26 forming the arm 25 and through a socket 31 which is secured by bolts 32 to the top of the press-member 9. The latter is usually formed of wood and has reinforcing cleats 9^a secured thereto. The pin 30 passes through a collar 33 and through elongated slots 34 in the socket 31. A spring 35 is interposed between the collar 33 so that pressure applied to the pin 30 through the arm 25 will be yieldingly applied through spring 35 to the upper press-member 9. This pin-and-slot connection also permits the presser-head 9 to accommodate itself to any unevenness or irregularity 95 in the box. Normally, the arm 25 is held in 100 raised position to hold the press-member 9 elevated, by a pair of springs 36 which are connected to said arm, as at 37, and to the sleeve, as at 38. The arm is adapted to be 105 swung about its pivot 28 to raise and lower the press-member 9 by a self-locking linkage comprising a pair of toggle links 39 and 40 pivoted to each other at 41 and to the arm 25, at 42, and to the sleeve 21 at 43, respectively. A lever 44 has its inner end 110

fulcrumed upon the pin 30 and provided with a handle 45 at its outer end. An operating rod 46 is pivoted to the lever 45 by a pin 47 and pivoted to the connecting pivot 41 between the toggle links. The latter are adapted to pass into dead-center relation, as shown in Fig. 1, and constitute a self-locking linkage adapted to hold the arm 25 in position to hold the press-member 9 against the box being sealed. Rod 46 is adapted to operate the toggle-links from lever 44 to release the linkage and permit arm 25 to lift the said press-member into raised position as shown in Fig. 1, where it will be held by springs 36. A stop 41^a may be provided between the links 39 and 40 to prevent them from passing beyond the dead-center when the lever 44 is lowered.

The operation of the improved machine will be as follows: The operator will place the box to be sealed upon the lower press-member 8, said member and the sleeve 21 having been first adjusted to set the members so they will operate upon the boxes of the height to be sealed. The operator will then grasp the handle 45 and lever 44 and pull it downwardly and forwardly until the rod 46 operated by the lever has operated the toggle-links into dead-center or self-locking position. This will lower arm 25 sufficiently to cause the press-member 9 to be operated against the flaps of the box to be sealed, the spring 35 serving to exert the desired pressure for sealing. When the handle and arm have been thus shifted, the toggle links will hold the upper press-member in operative relation to the box. The entire series of presses may then be rotated to bring the next press into position to receive a box. When the box has been sealed, the operator will lift lever 44 to operate rod 46 to shift the link-pivot 41 rearwardly and thus release the linkage and permit spring 36 to lift arm 25 and to press member 9.

If desired, the standard 10 may be raised so as to bring the member 8 sufficiently above the arm 12 to permit the bottom flaps of a box blank to be sealed by the press.

The invention exemplifies a box sealing machine which is simple in construction and in which one of the members of each press is raised and lowered by an automatic or self-locking connection so that it is only necessary for the operator to lower the upper press-member to bring and lock it into operative position. The entire upper series of press-members are conjointly adjustable to adapt the presses to boxes of different heights.

The invention is not to be understood as restricted to the details set forth, since these may be modified within the scope of the appended claims, without departing from the spirit and scope of the invention.

Having thus described the invention, what

I claim as new and desire to secure by Letters Patent, is:

1. In a box sealing machine, the combination of a pair of coacting press members, one of which is movable to and from the other, a supporting connection for movably sustaining the movable member, and a self-locking linkage for shifting and locking said connection and movable therewith.

2. In a box sealing machine, the combination of a pair of coacting press members, one of which is movable relatively to the other, a pivot arm for supporting the movable member, a support on which the arm is pivoted, and means for operating said arm comprising a self locking linkage between the support and the arm.

3. In a box sealing machine, the combination of a pair of coacting press members, one of which is movable relatively to the other, a pivot arm for supporting the movable member, a support to which the arm is pivoted, and means for operating said arm comprising a self locking linkage between the support and the arm and a lever pivotally connected to said arm.

4. In a box sealing machine, the combination of a pair of coacting press members, one of which is movable relatively to the other, a pivot arm for supporting the movable member, a support to which the arm is pivoted, means for operating said arm comprising a self-locking linkage between the support and the arm, a lever pivoted to the arm and a rod between the lever and the linkage.

5. In a box-sealing machine, the combination of a pair of coacting upper and lower press-members, an arm for supporting one of the press-members, means for operating the arm comprising a self-locking linkage, and a spring for retracting the arm.

6. In a box-sealing machine, the combination of a pair of coacting upper and lower press-members, an arm for supporting one of the press-members, means for operating the arm comprising a self-locking linkage, means for releasing the linkage and a spring for retracting the arm.

7. In a box-sealing machine, the combination of a pair of coacting upper and lower press-members, an arm for supporting one of the press-members and from which said latter member is pivotally suspended, means for operating the arm comprising a self-locking linkage pivoted to said arm, means for releasing the linkage, and a spring for retracting the arm.

8. In a box-sealing machine, the combination of a pair of coacting upper and lower press-members, an arm for supporting one of the press-members and from which the latter member is pivotally suspended, and means for operating the arm comprising a self-locking linkage, a lever pivoted to the

arm and a rod between the lever and the linkage.

9. In a box-sealing machine, the combination of a pair of coacting upper and lower press-members, an arm for supporting one of the press-members, from which said latter member is pivotally suspended, means for operating the arm comprising a self-locking linkage, a lever pivoted to the arm and a rod between the lever and the linkage, and a spring for retracting the arm.

10. In a box sealing machine, the combination of a base, a mast rotatably mounted in the base, a series of rotatable presses each comprising a pair of coacting upper and lower members, a carrier from which the lower members are supported, a carrier for the upper members, operating and supporting connections between said carrier and the upper members, and a vertically adjustable connection between the upper carrier and said mast.

11. In a box-sealing machine, the combination of a pair of coacting press-members, mechanism for operating one of them relatively to the other, and a pivotal support for one of the members comprising a pin, means

having elongated slots therein through which the pin passes and a spring in said socket and forming a resilient connection between 30 the pin and said means.

12. In a box-sealing machine, the combination of a pair of coacting press-members, mechanism for operating one of them relatively to the other, a pivotal support for one 35 of the members comprising a pin, a socket secured to said member and having elongated slots therein through which the pin passes, and a spring in said socket and forming a resilient connection between the pin 40 and the socket.

13. In a box-sealing machine, the combination of a pair of coacting press-members, mechanism for operating one of them relatively to the other, a support for one of the 45 members comprising a standard, a socket secured to said latter member and fitting over the standard, and a stop-pin for the socket on the standard, the latter member and the socket being removable by lifting 50 them from the standard without disconnecting the pin from the standard.

BERG HEINRICH'S.
